[57] CLAIM

The ornamental design for a golf club head, as shown and described.

DESCRIPTION

FIG. 1 is a perspective view, taken from the bottom of a golf club head according to our new design;

FIG. 2 is a bottom view thereof;

FIG. 3 is a top view thereof;

FIG. 4 is a toe side view thereof;

FIG. 5 is a heel side view thereof;

FIG. 6 is a front view thereof;

FIG. 7 is a rear side view thereof;

FIG. 8 is a perspective view, taken from the bottom, of a second embodiment of a golf club head according to our new design;

FIG. 9 is a bottom view of FIG. 8;

FIG. 10 is a top view of FIG. 8;

FIG. 11 is a toe side view of FIG. 8;

FIG. 12 is a heel side view of FIG. 8;

FIG. 13 is a front view of FIG. 8;

FIG. 14 is a rear view of FIG. 8;

FIG. 15 is a perspective view, taken from the bottom, of a third embodiment of a golf club head according to our new design;

FIG. 16 is a bottom view of FIG. 15;

FIG. 17 is a top view of FIG. 15;

FIG. 18 is a toe side view of FIG. 15;

FIG. 19 is a heel side view of FIG. 15;

FIG. 20 is a front view of FIG. 15;

FIG. 21 is a rear view of FIG. 15.
